US0D1109029S

(12) **United States Design Patent** (10) **Patent No.:** **US D1,109,029 S**
(45) **Date of Patent:** **** Jan. 13, 2026**

(54) **FOUR WHEELED ROLLATOR**

(71) **Applicant:** **Foshan Ost Medical Equipment Technology Co., Ltd.**, Foshan (CN)

(72) **Inventor:** **Bin Wang**, Foshan (CN)

(73) **Assignee:** **Foshan Ost Medical Equipment Technology Co., Ltd.**, Foshan (CN)

(**) **Term:** **15 Years**

(21) **Appl. No.:** **29/951,779**

(22) **Filed:** **Jul. 11, 2024**

(51) **LOC (15) Cl.** **12-12**

(52) **U.S. Cl.**

USPC **D12/130**

(58) **Field of Classification Search**

USPC D6/333; D21/535, 664-665, 682;

D12/128-133

CPC A61H 2003/046; A61H 2003/043; A61H

2003/007; A61H 2003/001; A61H 3/00;

A61H 3/04
